HANDBAG OR THE LIKE

Cecilio I. Lazo de la Vega, P.O. Box 554,
Valdosta, Ga. 31601

Filed Mar. 30, 1972, Ser. No. 239,845

Term of patent 14 years

Int. Cl. D3—01

U.S. Cl. D3—87 F

FIG. 1 is a front elevational view of a handbag showing my new design;

FIG. 2 is an end elevational view thereof;

FIG. 3 is a top plan view, the handstrap being broken away for convenience of illustration;

FIG. 4 is a rear elevational view thereof;

FIG. 5 is a front perspective view of the handbag in an open condition; and

FIG. 6 is a front perspective view on a reduced scale showing a second embodiment of the design the entire quarter forming the lid portion which is in a partially open condition.

I claim:

The ornamental design for a handbag or the like, substantially as shown and described.
